DESIGN FOR A LAMP OR SIMILAR ACCESSORY FOR VEHICLES

Carl E. Meyerhoefer, Brooklyn, N. Y., assignor to E. A. Laboratories, Inc., Brooklyn, N. Y., a corporation of New York

Application July 20, 1936, Serial No. 63,942

Term of patent 14 years

To all whom it may concern:

Be it known that I, Carl E. Meyerhoefer, a citizen of Germany who has declared his intention of becoming a citizen of the United States, residing in Brooklyn, Kings County, New York, have invented a new, original, and ornamental Design for a Lamp or Similar Accessory for Vehicles, of which the following is a specification, reference being had to the accompanying drawing, forming part thereof.

Figure 1 is a side elevation, and Figure 2 is a front elevation of a lamp or similar accessory for vehicles, showing my new design.

I claim:

The ornamental design for a lamp or similar accessory for vehicles, as shown.

CARL E. MEYERHOEFER.
